EXERCISING MACHINE

James Maratta, Pelham, N.Y., assignor to Physio-Health,
Inc., Pelham, N.Y., a corporation of New York

Filed Mar. 14, 1962, Ser. No. 69,254

Term of patent 14 years

(Cl. D34—5)

FIG. 1.

FIG. 2.

I claim:

The ornamental design for an exercising machine, as shown.
